PHARMACEUTICAL PREPARATION FOR RELIEVING ITCH AND KILLING ACARIDAE

Henry Martin and Alfred Margot, Basel, Switzerland, assignors to J. R. Geigy A. G., Basel, Switzerland, a Swiss firm

No Drawing. Application June 23, 1947, Serial No. 756,550. In Switzerland June 28, 1946

7 Claims. (Cl. 167—58)

1

Acaridae (mites) are widespread pests. Many kinds lead a parasitic life on host organisms, such as plants, animals and human beings, causing considerable harm. The condition brought about by mite attacks on humans is called scabies or "the itch." Itch mites are parasitic, burrowing and breeding in the skin, causing eruptions and constant irritation. (See Webster's New International Dictionary under "itch mite.") The textbooks on dermatology provide substantially the same information. (Consult Becker and Obermayer, "Modern Dermatology and Syphilology" (1940), p. 486; Schwartz, Tulipan, and Peck, "Occupational Diseases of the Skin" (2nd ed. 1947), p. 602; Ormsby and Montgomery, "Diseases of the Skin" (6th edition), p. 1138.)

Acaridae differ from insects partly by their biology but also have essential anatomical and physiological dissimilarities. For this reason it is not astonishing that insecticides show no or only insufficient action against Acaridae. For example, the well-known $\alpha:\alpha$ -bis-(p-chlorphenyl)- $\beta:\beta$ -trichlorethane is inactive against most Acaridae. Also other natural and synthetic insecticides have no marked effect on Acaridae.

It has now been found that amides of $\alpha:\beta$ -unsaturated carboxylic acids of the general formula

wherein

R_1 and R_2 mean hydrogen or methyl, R_3 means hydrogen or alkyl and

R_4 means a phenyl radical, which in certain cases contains substituted, non-saltforming groups,

are very effective for combating Acaridae. Amides deriving from secondary amines, viz. in which R_4 is an alkyl radical, are preferred.

Amides of this formula are known to some extent. They may be obtained for example, by reacting the corresponding $\alpha:\beta$ -unsaturated carboxylic acid chlorides with aniline, its homologues or its derivatives substituted by non-salt-forming groups. The term "non-saltforming groups" in the above definition is taken to mean, for example: halogen, alkyl-, alkoxy-groups and so on.

Example A

The following compounds have proved to be still effective at a concentration of 10^{-6} g./cm.² against the red spider (*Paratetranychus humilis*), which is particularly difficult to combat:

2

5	Compound	Action: kill Time	
		Percent	Hours
1	Crotonic acid-N-methyl-anilide	80	24
2	β,β -Dimethylacrylic acid-N-methyl-anilide	94	24
3	β,β -Dimethylacrylic acid-N-methyl-p-toluidide	90	24
4	β,β -Dimethylacrylic acid-N-methyl-o-chloranilide	81	48

Example B

The following test results were observed with flour mites (*Aleurobius farinae*) and cheese mites (*Tyroglyphus stro*) at a concentration of 10^{-4} g./cm.²:

20	Compound	Aleur. far. kills	Time	Tyrog. stro kills	Time
		Per cent	Hours	Per cent	Hours
1	Crotonic acid-N-methyl-anilide	94	8	160	1
2	Crotonic acid-N-ethyl-anilide	90	24		
3	Crotonic acid-N-methyl-o-toluidide	83	8	83	8
4	Crotonic acid-N-ethyl-o-toluidide	91	8	87	8
5	Crotonic acid-N-methyl-p-toluidide	95	0.5		
6	Crotonic acid-N-methyl-o-chloranilide	100	8		
7	β,β -Dimethylacrylic acid-N-methyl-anilide	100	2	100	8
8	β,β -Dimethylacrylic acid-N-ethyl-anilide	81	2	100	0.5
9	β,β -Dimethylacrylic acid-N-methyl-o-toluidide	100	24	90	2
10	β,β -Dimethylacrylic acid-N-methyl-p-toluidide	80	24	100	24
11	β,β -Dimethylacrylic acid-N-methyl-o-chloranilide	95	24	91	24
12	Trimethylacrylic acid-N-methyl-o-toluidide	83	0.5	87	2
30		100	2	92	24
13		75	24	100	24

Example C

The use of the following compounds in 10% acetone solution resulted in the complete extermination of a further type of mite, *Psoroptes cuniculi*, inside 48 hours:

50	Compound	B. Pt. °C. (mm.)	M. Pt. °C.
1	Crotonic acid-anilide		110-115
2	Crotonic acid-N-methyl-anilide	147-150 (13)	
3	Crotonic acid-N-ethyl-anilide	152-154 (13)	
4	Crotonic acid-N-methyl-o-toluidide	144-148 (13)	
5	Crotonic acid-N-methyl-p-toluidide	153-158 (12)	
6	Crotonic acid-N-ethyl-o-toluidide	153-155 (13)	

	Compound	B.Pt.°C. (mm.)	M.Pt.°C.
7	Crotonic acid-N-ethyl-p-toluidide	159-163 (11)	.....
8	Crotonic acid-N-ethyl-m-toluidide	157-160 (11)	.....
9	Crotonic acid-N-ethyl-o-chloranilide	169-173 (13)	.....
10	Crotonic acid-N-ethyl-p-bromanilide	127-130 (0.1)	.....
11	Crotonic acid-N-ethyl-3,4-dichloranilide	138-141 (0.1)	10
12	Crotonic acid-N-ethyl-2-chlor-6-methyl-anilide	118-121 (0.05)	.....
13	Crotonic acid-o-anisidide	.....	77-79
14	Crotonic acid-N-methyl-p-anisidide	135-140 (0.1)	.....
15	Crotonic acid-N-ethyl-o-anisidide	133-138 (0.15)	15
16	Crotonic acid-N-isoamyl-o-toluidide	134-138 (0.1)	.....
17	β,β - Dimethyl - acrylic acid-N-methyl-anilide	145-146 (13)	.....
18	β,β - Dimethyl - acrylic acid-N-ethyl-anilide	148-150 (13)	20
19	β,β - Dimethyl - acrylic acid-N-isobutyl-anilide	122-125 (0.3)	.....
20	β,β - Dimethyl - acrylic acid-N-methyl-o-toluidide	145-150 (12)	.....
21	β,β - Dimethyl - acrylic acid-N-ethyl-o-toluidide	150-152 (13)	.....
22	β,β - Dimethyl - acrylic acid-N-isoamyl-o-toluidide	126-129 (0.2)	25
23	β,β - Dimethyl - acrylic acid-N-ethyl-m-toluidide	155-158 (11)	.....
24	β,β - Dimethyl - acrylic acid-N-ethyl-p-toluidide	160-163 (11)	.....

26	β,β - Dimethyl - acrylic acid-p-chloranilide	122-124	30
27	β,β - Dimethyl - acrylic acid-N-ethyl-p-bromanilide	121-126 (0.1)	.....
28	β,β - Dimethyl - acrylic acid-N-methyl-o-chloranilide	168-172 (13)	.....
29	β,β - Dimethyl - acrylic acid-N-ethyl-m-chloranilide	114-116 (0.05)	.....
30	β,β - Dimethyl - acrylic acid-N-ethyl-3,4-dichloranilide	123-126 (0.05)	35
31	β,β - Dimethyl - acrylic acid-N-ethyl-2-chlor-6-methyl-anilide	117-118 (0.05)	.....
32	β,β - Dimethyl - acrylic acid-N-ethyl-o-anisidide	126-130 (0.2)	.....
33	β,β - Dimethyl - acrylic acid-N-methyl-p-anisidide	134-138 (0.1)	40
34	β,β - Dimethyl - acrylic acid-N-ethyl-p-phenetidide	143-148 (0.2)	.....
35	Trimethyl-acrylic acid-N-methyl-anilide	115-119 (0.4)	.....
36	Trimethyl-acrylic acid-N-methyl-o-toluidide	148-150 (12)	.....
37	Trimethyl-acrylic acid-N-ethyl-o-toluidide	152-156 (12)	.....
38	Trimethyl-acrylic acid-N-ethyl-m-toluidide	153-157 (12)	45
39	Trimethyl-acrylic acid-N-methyl-p-toluidide	153-157 (12)	.....
40	Trimethyl-acrylic acid-N-ethyl-m-chloranilide	121-125 (0.05)	.....
41	Trimethyl-acrylic acid-N-ethyl-p-bromanilide	121-126 (0.1)	50
42	β,β - Dimethyl-acrylic acid-di-chlor-anilide (Mixture of isomers)	80-90	.....
43	Trimethyl-acrylic acid-N-methyl-p-anisidide	130-135 (0.1)	.....
44	Trimethyl-acrylic acid-N-ethyl-p-phenetidide	139-143 (0.1)	.....

It should be noted, however, that in most cases the limit of effective concentration is considerably lower. Furthermore, the mites become paralysed in a very short space of time so that already long before death they are unable to cause any more damage. As is explained below, the compounds have bactericidal properties in addition to being acaricidal. Further since they are practically odourless and non-toxic in the concentration necessary, they are eminently suitable for the preparation of acaricidal media for use not only to protect plants and stores, but also for general hygiene.

The active compounds should not be used in their original form but diluted, thus allowing better and more economical use to be made of them. In general, an approximately 5-10% concentration in the mixture as used has been found sufficient. However, in certain cases, e. g., with aqueous emulsions, it is possible to employ much lower concentrations with success. In the case

of preparations in powder form, e. g., media for dusting or powdering where contact with the mites is not so intimate as with liquid preparations, higher concentrations up to e. g. 80% can be utilised. A fine, even dispersion of the active substance in the product when ready for use is of importance as regards the efficiency of the medium preparable according to the invention. In concentrates, e. g., concentrated emulsions, which need to be diluted before use, the active agent must be present in a form which can be dispersed both rapidly and finely. Such a fine dispersion can be achieved, for example, by mixing and milling the active agent with a solid, pulverulent extending agent to the desired degree of fineness or by impregnating the already milled, finely powdered, solid carrier with a solution of the active agent in a volatile solvent and then removing the latter, which can be recovered when desired, e. g., by suction at reduced pressure. The particle size of the final product should not exceed ca. 300 microns. An advantageous particle size is from 20-80 microns.

Such fine dispersions can also be brought about by emulsifying the active ingredient or a solution of the same with the aid of a dispersing—or emulsifying—agent. In the emulsions the active ingredient is present, dispersed in particles ranging from fine to colloidal size. The particle size should in general not be more than 200 microns. An advantageous particle size is, however, below 10 microns.

The invention can also be used in the form of a solution of the active ingredient in suitable inert liquid or semi-solid extending agents where the active agent is dispersed in molecular size. The mode of employment varies according to the uses intended. As solid carriers, which are suitable for the manufacture of pulverulent preparations, various inert, porous and pulverulent distributing agents of an inorganic or organic nature may be employed, for example, tricalcium phosphate, calcium carbonate in the form of whiting or ground chalk or limestone, kaolin, bole, bentonite, talcum, calcined magnesia, kieselguhr, boric acid, also powdered cork, powdered wood and other pulverulent materials of vegetable origin are suitable carrier substances. By adding wetting and/or dispersing agents, such pulverulent preparations can be rendered easily wettable by water so as to obtain stable suspensions suitable for use as spraying agents, for example, in plant protection.

Inert solvents suitable for the production of liquid preparations should not be easily inflammable and should be as odourless as possible and, when used properly, should be as non-toxic as possible towards men and animals. Also they should be non-corrosive towards the active component as well as towards the materials of the storage vessels. The following solvents may be employed for this purpose: On the one hand, high-boiling oils, for example, oils of vegetable origin, such as castor-oil and the like; on the other hand, also low boiling solvents with a flash point of at least 30° C., such as, for example, carbon tetrachloride, ethylene dichloride, tetrachlorethane, hydrogenated naphthalenes, alkylated naphthalenes, solvent naphtha or the like. Obviously, mixtures of solvents may also be employed. The preparation of solutions is carried out in the usual manner, if required, with the aid of solubility promoters.

Other practical liquid forms consist of emulsions or suspensions of the active component in water or suitable inert solvents, or of concentrates

for preparing such emulsions which can be adjusted to the desired working concentration by dilution at the place of use. For this purpose, the active component is mixed with a dispersing or emulsifying agent. The active component may also be dissolved or dispersed in a suitable inert solvent and mixed at the same time or subsequently with a dispersing or emulsifying agent. By diluting such a concentrate, for example with water, emulsions or suspensions ready for use are obtained. With a suitable concentration and mixing proportion of active component, emulsifying agent and water, clear, entirely stable aqueous solutions (emulsoids) can be obtained.

Various capillarily active substances with an anion-active or a cation-active or a non-ionising component may be employed as dispersing or emulsifying agents. There may be mentioned, by way of example, natural or synthetic soaps, Turkey red oil, fatty-alcohol sulphonates, sulphated fats, esters of fatty acids, and the like, also higher molecular quaternary ammonium compounds, as well as condensation products of aliphatic or araliphatic compounds and ethylene oxide, for example, the condensation product of stearin alcohol and ethylene oxide.

For special purposes, semi-solid extenders of the nature of a cream, ointment, paste or wax may be employed, into which the active substance can be worked, with the aid of solubility-promoters and/or of emulsifying agents, if required. Such semi-solid preparations are mostly emulsions. Soft soap (potassium stearate) or Vaseline may be mentioned as examples of semi-solid extenders.

The active component itself may consist of one or more compounds of the formula defined. Also, it may be used together with other organic synthetic acaricides, insecticides, ovicides, fungicides or bactericidal substances. There may be mentioned, by way of example as other substances of this kind: benzyl benzoate, dimethyl thianthrene, phthalonitile, $\alpha:\alpha$ -bis-(chlorophenyl)- $\beta:\beta$ -trichlorethane or - $\beta:\beta$ -dichlorethane (DDT and DDD), dinitroresol, nitrated naphthylamine, mercury compounds or inorganic substances such as copper compounds, sublimate or sulphur. Composite preparations with a great range of effectiveness are obtained in this manner.

It is also possible to employ the active component in the form of aerosols. For this purpose, the active component is dissolved or dispersed, with the aid of suitable inert solvents as carrier liquids, if required, in a solvent such as Freon

which boils below room temperature at atmospheric pressure. There are thus obtained solutions under pressure which, on being sprayed, give aerosols which are specially suitable for combating mites in closed spaces, in grain silos and other store rooms. The active ingredient, in a suitable solvent, can also be sprayed using compressed gases, e. g., air.

The following may be mentioned as further additives which can be mixed with the various forms of composition (Acaridae combating compositions) mentioned: adhesive substances such as casein, salts of fatty acids, glue, resins, fats, albumen-degradation products; wetting agents, solubility promoters, dyestuffs and perfumes and, in the case of pulverulent preparations, dust-binding media and so on.

It is quite possible, by selecting the various extenders and additives, to give the agents such a composition and properties, depending thereon, as to render them suitable for special purposes or conditions of employment. Thus, it is possible to produce, for example, dips, sprinkling agents, and spraying agents in the form of emulsions or suspensions, as well as emulsions and suspensions for general use and concentrates for their preparation. The agents mentioned are mostly liquid preparations. The following are solid preparations: dusting agents, drying powder, strewing agents and such like, and also solid soap preparations which can be employed in the form of moulded pieces.

The present Acaridae combating agents can be applied by methods of application usual for insecticides. The Acaridae or the materials, for example, plants, roots, root nodules, drugs, textiles, packing materials, cereals, dried fruits, stores of foodstuffs and fodder, seeds, wood, leather, skins, paper, furs, hair, feathers, articles of all kinds, carpets, walls and floors, which are to be treated or protected from attack by or harbourage of Acaridae, can be treated with the active component or with the agents described, by dusting, strewing, sprinkling, painting, smearing, impregnating or other suitable methods.

As mentioned at the beginning, the active compounds having the formula defined have a strong bactericidal or growth-inhibiting action on various sources of infection, such as, e. g., Streptococci and Staphylococci. The action on *Staphylococcus aureus* is revealed in the following experimental results. The tests for bacteriostatic activity were carried out using a modified plate method due to Flemming:

	Compound (5 mg. quantities)	B. Pt. °C./mm.	Inhibition Diameter, mm.		
			Staphylo- cocci	Strepto- cocci	Diph- theria bacilli
1	Crotonic acid-N-methyl-o-toluidide	144-148/13	7-10	3	9
2	Crotonic acid-N-ethyl-o-toluidide	153-155/13	7-8	10	7
3	Crotonic acid-N-ethyl-p-toluidide	159-163/11	7		
4	Crotonic acid-N-ethyl-p-bromanilide	127-130/0.1	4-5	6	
5	Crotonic acid-N-ethyl-2-chlor-6-methyl-anilide	118-121/0.05	6-7	7	8
6	Crotonic acid-N-methyl-p-anisidine	135-140/0.1	5		
7	Crotonic acid-N-ethyl-p-phenetidine	143-147/0.1	7		
8	$\beta:\beta$ -Dimethylacrylic acid-N-methyl-anilide	145-149/13	5		
9	$\beta:\beta$ -Dimethylacrylic acid-N-methyl-o-toluidide	145-150/12	7-11	7	7
10	$\beta:\beta$ -Dimethylacrylic acid-N-ethyl-o-toluidide	150-152/13	5	6	6
11	$\beta:\beta$ -Dimethylacrylic acid-N-isopropyl-o-toluidide	116-119/0.4	5		
12	$\beta:\beta$ -Dimethyl-acrylic acid-N-methyl-p-toluidide	152-155/12	8-9	6	9
13	$\beta:\beta$ -Dimethylacrylic acid-N-ethyl-p-toluidide	160-163/11	6-7	4	6
14	$\beta:\beta$ -Dimethyl-acrylic acid-N-ethyl-2-chlor-6-methyl-anilide	117-119/0.05	9-14	5	7
15	$\beta:\beta$ -Dimethyl-acrylic acid-N-methyl-p-anisidine	134-138/0.1	6		
16	Trimethyl-acrylic acid-N-methyl-o-toluidide	148-150/12	7		
17	$\beta:\beta$ -Trimethyl-acrylic acid-N-ethyl-m-toluidide	153-157/12	4	3	9
18	Trimethyl-acrylic acid-N-ethyl-o-anisidine	168-174/11	6-7	4	7
19	Trimethyl-acrylic acid-N-methyl-p-anisidine	130-135/0.1	5		
20	Trimethyl-acrylic acid-N-ethyl-p-phenetidine	139-143/0.1	5		
21	Comparison compound iodo-chloro-oxyquinoline		3-5	5-6	4

Thus the agents prepared according to the invention can also be used as disinfectants in the event of a disinfectant action being necessary or desired. Accordingly, articles of clothing or underwear, implements, utensils and other articles as well as living-rooms, surgical instruments and adjuvants can all be disinfected using the agents.

Also, agents which contain the active component herein defined are very suitable for cleaning and washing warm-blooded animals attacked by mites. The following are particularly suitable extending agents for this purpose: liquid extenders, e. g., paraffin oil or vegetable oils such as olive oil, castor oil, sesame oil, camphor oil and also glycerine or solvent-mixtures, e. g., containing glycerine, and so on. Suitable semi-solid extenders, e. g., Vaseline, wool fat and the like, or mixtures of such materials. Suitable emulsifying agents for the preparation of aqueous solutions and emulsions, for example, are above all soaps, but also sulphonated fats, fatty acid esters and fatty alcohol sulphonates, alkylated aromatic and hydrogenated aromatic sulphonic acids, higher molecular alkoxy carboxylic acids, e. g., alkoxy acetic acids as well as non-ionising emulsifying agents, such as condensation products of fatty alcohols with ethylene oxide. Esters of phosphoric acid are also satisfactory emulsifying agents. However, emulsions of ointment-like consistency can be produced, for example by employing stearic acid, fatty acid salts and water. For the production of fat-free ointments, cellulose ether bases may be employed, or other steeping or swelling substances of animal, vegetable or synthetic origin and water or inorganic substances, such as aluminium-hydroxide gel, in which the active substances can be incorporated, if necessary with the aid of emulsifying agents and/or solubility agents such as paraffin oil. If desired, the preparations obtained may be perfumed by the addition of perfumes. Examples of good, adhesive pulverulent carrier substances are, talcum, starch, lactose and the like.

Many other solids can also be used as carriers, e. g., textile fabrics, cotton, wool, sheets of paper or water-soluble celluloses, which can be for example impregnated with the active ingredient.

Furthermore, the bactericidal action can be extended by the addition of phenols, such as p-chlor-m-cresol, o-butyl-p-chlorphenol, o-benzyl-p-chlorphenol, chlorxylenol, cyclohexylphenol, oxydiphenyl and similar compounds. The active ingredients may also be combined with many other disinfectants and fungicides, e. g., with quaternary ammonium compounds such as dodecyl-benzyl-trimethyl-ammonium-metho-sulphate, oxyquinoline derivatives, colloidal silver preparations, thiocyanic acid etc. In special cases an auxiliary substance such as wetting agent can also have bactericidal action and increase thereby the disinfectant action of the medium. Foam producing substances are also particularly effective for this purpose, such as, e. g., ordinary or synthetic soaps, saponines and so on.

The amides used as active ingredients show, in part, a high dissolving power for other compounds which are themselves only difficultly soluble in the solvents used in the manufacture of acaricidal or disinfectant media. Thus it is possible for example, to dissolve up to 10% of 5:7-dichlor-8-oxyquinaldine at room temperature in crotonic acid-N-ethyl-o-toluidide.

Various modes of preparation of the acaricidal media as well as their uses are described in the

following examples. The invention is not restricted to these examples, however. The parts are given throughout by weight.

Example 1

5 parts of crotonic-acid-N-ethyl-o-toluidide (B. P. at 13 mm. 153-155° C.) are ground together with 92 parts of talcum in a ball mill, 2 parts of olein are then added, the whole is again ground and is finally mixed with 1 part of slaked lime. The resulting powder is easily scattered and has good adhesive power. It can be employed for the dusting of rooms and articles or for the protection of plants. A still better distribution of the active substance over or in the carrier material is obtained when the carrier is impregnated with a solution of the active substance, in alcohol or acetone, for example, and the solvent then evaporated.

Example 2

15 parts of crotonic-acid-N-ethyl-o-toluidide are mixed with 22.3 parts of kaolin; 4 parts of the sodium salt of dibutylnaphthalenesulphonic acid, 4 parts of casein and 4.7 parts of soda are added and the whole is ground. 100 parts of finely ground chalk are then mixed in. The resulting powder gives, in water, a sufficiently stable suspension which can be employed for spraying rooms and articles attacked by mites and, for example, also for the protection of plants.

Instead of 15 parts of crotonic-acid-N-ethyl-o-toluidide, there may be employed: 5 parts of crotonic-acid-N-ethyl-o-toluidide and 10 parts of DDT ($\alpha:\alpha$ -bis-(p-chlorophenyl)- $\beta:\beta$ -trichlorethane) or 10 parts of crotonic-acid-N-ethyl-o-toluidide and 5 parts of said DDT.

Example 3

40 80 parts of $\beta:\beta$ -dimethylacrylic-acid-N-ethyl-anilide (melting point 43° C.) are finely ground together with 20 parts of talc. This concentrate can be employed directly as strewing powder for combating mites. However, it may be diluted to any desired concentration, e. g., with bentonite. The addition of urea gives a strewing-powder particularly effective for purposes of disinfection.

Such powders, which can also be produced on other principles are suitable as dusting agents, for example for combating mites on human or animal skin. Powder preparations, for example with a basis of starch-flour, may also be employed for combating mites in storehouses, by mixing with grain for example. If necessary, substances may be added for improving adhesion, for which purpose, for example, an addition of 4% of a liquid fatty acid is suitable.

Example 4

60 5 parts of crotonic-acid-N-ethyl-o-toluidide or -m-toluidide are dissolved in 95 parts of alkylated naphthalene (Velsicol) and employed as a household spraying agent.

Example 5

65 By mixing 10 parts of crotonic-acid-N-ethyl-o-toluidide with 90 parts of olive oil, a clear solution is obtained which can be employed for combating mites.

Example 6

70 30 parts of crotonic-acid-N-ethyl-o-toluidide or -anilide and 70 parts of a fatty-acid-ester sulphonate give a clear solution which can be diluted with any desired quantity of water. A milky emulsion is first produced which, however,

turns into a stable, presumably colloidal solution (emulsoid) when sufficient water is added to make concentration of the active substance about 7%.

As fatty-acid-ester sulphonate, Turkey-red oil, for example, may be employed. The proportion of active substance to emulsifier may be varied; thus, for example, a similar emulsion is obtained on employing 40 parts of crotonic-acid-N-ethyl-o-toluidide and 60 parts of emulsifier.

Such solutions or emulsions can be employed with advantage for the most various purposes. Thus, they are suitable for spraying in rooms attacked or threatened by mites. Moreover, articles of different kinds, which have been attacked by mites or which to be protected from attack by mites, may be sprayed with, or impregnated by immersion in, this solution. Sacks made of fabric or paper or other packing materials, which have been impregnated with this solution, are suitable for the mitefree storage of provisions or other stores. Similarly, these emulsions may be employed for the protection of plants.

Also, parts of the body of human beings and animals which have been attacked by mites can be treated with such a solution. For this purpose, the solution can be brushed or smeared on. For treating small animals, it is advantageous to use such a liquid as a bathing liquid.

Example 7

30 parts of crotonic-acid-N-ethyl-o-toluidide, 30 parts of xylene and 40 parts of Turkey-red oil are mixed to give a clear solution which can be emulsified in water in any proportion. This emulsion is employed as in Example 6.

Example 8

A homogeneous paste is obtained by stirring 30 parts of crotonic-acid-N-ethyl-o-toluidide with 70 parts of potash soap. By diluting this paste with water, an emulsion is obtained which is suitable as a washing liquid with mite-exterminating and disinfectant properties.

Example 9

By stirring 7 parts of crotonic-acid-N-ethyl-o-toluidide with 93 parts of alcoholic soap solution, a clear solution is obtained. More concentrated solutions may also be produced which turn into emulsions on being diluted with water. Instead of 7 parts of crotonic-acid-N-ethyl-o-toluidide, 5 parts of crotonic-acid-N-ethyl-o-toluidide and 2 parts of chloroxylenol may be used, giving a disinfectant washing liquid in dilution with water.

Example 10

1.4 parts of p-tolyl-dodecyl-trimethyl-ammonium-methosulphate and 49 parts of crotonic-acid-N-ethyl-o-toluidide are dissolved in 49.6 parts of alcohol. This clear solution gives an emulsion on dilution with water which is suitable for combating mites as described in Example 6. It is also effective, however, for disinfecting equipment of all kinds.

Example 11

8 parts of paraffin, 15 parts of stearic acid, 5 parts of wool fat and 2 parts of wax are heated together to 80° C. At this temperature there are stirred in 3 parts of glycerine, 1 part of triethanolamine, 58.5 parts of water (previously heated to 80° C.) and 0.5 part of concentrated ammonia. The finished ointment base is stirred with 7 parts of crotonic-acid-N-ethyl-o-toluidide, with the result that a homogeneous cream with a powerful

mite-exterminating and disinfectant action is obtained, which is specially suitable for treating parts of the skin which have been attacked by mite.

Example 12

3 parts of methyl cellulose are soaked in 90 parts of hot water and the swollen mass obtained is intimately mixed with 7 parts of crotonic-acid-N-ethyl-o-toluidide. A fat-free acaricidal ointment is thus obtained. Instead of methyl cellulose, other swelling substances, such as tragacanth, gelatins or alginates, may be employed.

Example 13

7 parts of crotonic-acid-N-methyl-anilide (B. P. at 13 mm., 145-148° C.) are stirred with 93 parts of vaselinum flavum until uniform distribution is obtained. An ointment with good acaricidal effect is obtained. By diluting with suitable solvents, the ointment can be given a thinner consistency. An ointment with a good bactericidal action is obtained which is also suitable for combating mites, e. g., *Tyroglyphus*.

Example 14

A solution of 5 parts of $\alpha:\beta$ -dimethylacrylic acid-N-methyl-anilide (B. P. at 13 mm., 145-148° C.) 5 parts of cyclohexanone and 90 parts of Freon can be employed as a pressure solution for an aerosol bomb. When sprayed, an aerosol is obtained which is specially suitable for combating mites in enclosed spaces such as, for example, in grain silos. It is equally suitable for use for purposes of disinfection, e. g., of hospitals.

Example 15

7 parts of crotonic-acid-N-ethyl-o-toluidide (B. P. at 13 mm., 153-155° C.) are mixed with 8.5 parts of fatty acid-ester-sulphonate and 84.5 parts of water. This produces a practically clear, stable, probably colloidal solution suitable for purposes of disinfection, e. g., of surgical instruments.

Instead of this working-solution, a concentrate may be prepared, e. g., from 45 parts of crotonic acid-N-ethyl-o-toluidide and 55 parts of fatty acid-ester-sulphonate. On dilution with water there results at first an emulsion which however goes into solution when sufficient water is added to reduce the concentration of the active component to about 7%.

Example 16

15 parts of fatty alcohol sulphonate, prepared from a fatty alcohol with a carbon chain of 8-10 carbon atoms, 7 parts of crotonic acid-N-ethyl-o-toluidide are mixed with 78 parts of water to give an emulsion suitable, for example, for the disinfection of living-rooms.

Example 17

93 parts of bentonite are saturated with a solution of 7 parts of crotonic acid-N-ethyl-o-toluidide in acetone. Next, the solvent is removed in vacuo. The product is a disinfectant powder suitable for strewing which is also effective against mites.

What we claim is:

1. A pharmaceutical preparation for treating human skin eruption and irritation, comprising a creamy preparation containing a substantial amount of a creamy vehicle carrying crotonic

11

acid-N-ethyl-o-toluidide, said creamy preparation being adapted to be spread or smeared directly upon the human skin and over affected parts to afford relief for such condition after contact with said affected parts, said preparation being non-toxic and non-irritating.

2. A pharmaceutical preparation for treating human skin eruption and irritation, comprising a creamy preparation containing a substantial amount of a creamy vehicle carrying an active ingredient distributed therethrough, said active ingredient comprising essentially a carboxylic acid amide of the formula

wherein

R₁ and R₂ represent a member selected from the group consisting of hydrogen and methyl, R₃ represents a member selected from the group consisting of hydrogen and alkyl, and R₄ represents a phenyl radical substituted by no more than two members selected from the group consisting of hydrogen, halogen, alkyl and alkoxy radicals, and no more than one of said members being methyl.

said creamy preparation being adapted to be spread or smeared directly upon the human skin and over affected parts to afford relief for such condition after contact with said affected parts, said preparation being non-toxic and non-irritating to such irritated skin and compatible to human skin.

3. A pharmaceutical preparation of the character set forth in claim 2 wherein the active ingredient is present in the preparation at a concentration not substantially in excess of 10%.

4. A pharmaceutical preparation for direct application to the skin of human beings and effective in relieving skin irritation such as results from mite attacks and the like, comprising a substantial amount of a vehicle, said vehicle being compatible with human skin, containing an active ingredient distributed therethrough, said active ingredient comprising essentially a carboxylic acid amide of the formula

wherein

R₁ and R₂ represent a member selected from the group consisting of hydrogen and methyl, R₃ represents a member selected from the group consisting of hydrogen and alkyl, and R₄ represents a phenyl radical substituted by no more than two members selected from the group consisting of hydrogen, halogen, alkyl and alkoxy radicals, no more than one of said members being methyl.

said preparation being oily, compatible to human skin and being adapted to be spread or smeared directly upon such skin and over affected parts to afford relief for such condition after contact with said affected parts, wherein the active ingredient is present at a concentration of approximately 5% to approximately 10%.

5. A pharmaceutical preparation for treating human skin eruption and irritation comprising a vehicle, said vehicle being compatible to human skin, containing an active ingredient distributed therethrough, said active ingredient comprising

12

essentially a carboxylic acid amide of the formula

wherein

R₁ and R₂ represent a member selected from the group consisting of hydrogen and methyl, R₃ represents a member selected from the group consisting of hydrogen and alkyl, and R₄ represents a phenyl radical substituted by no more than two members selected from the group consisting of hydrogen, halogen, alkyl and alkoxy radicals, and no more than one of said members being methyl.

said preparation being non-toxic and non-irritating to such skin, and being adapted to be spread or smeared directly upon such skin and over affected parts to afford relief for such condition after contact with said affected parts, wherein the active ingredient is present in said preparation at a concentration of approximately 5% to approximately 10%.

6. A pharmaceutical preparation for treating human skin eruption and irritation, comprising a creamy preparation containing a substantial amount of a creamy vehicle carrying crotonic acid-N-ethyl-anilide, said creamy preparation being adapted to be spread or smeared directly upon the human skin and over affected parts to afford relief for such condition after contact with said affected parts, said preparation being non-toxic and non-irritating.

7. A pharmaceutical preparation for treating human skin eruption and irritation, comprising a creamy preparation containing a substantial amount of a creamy vehicle carrying crotonic acid-N-ethyl-o-toluidide, said creamy preparation being adapted to be spread or smeared directly upon the human skin and over affected parts to afford relief for such condition after contact with said affected parts, said preparation being non-toxic and non-irritating.

HENRY MARTIN.
